[57] CLAIM

The ornamental design for a medallion, substantially as
shown and described.

DESCRIPTION

FIG. 1 is a perspective view of the medallion showing
my new design;

FIG. 2 is a top plan view thereof;

FIG. 3 is a side elevational view thereof looking from
the right hand side of FIG. 2;

FIG. 4 is a side elevational view thereof looking from
the bottom of FIG. 2;

The side of the medallion not shown is a mirror image
of the side shown.
